DENTAL MIRROR

John Stuart Fleming, Niagara Falls, N.Y., assignor to Flexite Company, Inc., Niagara Falls, N.Y., a corporation of New York

Filed Feb. 26, 1969, Ser. No. 15,919

Term of patent 14 years

Int. Cl. D24—03

U.S. Cl. D24—1

I claim:

The ornamental design for a dental mirror, as shown.
